UNITED STATES PATENT OFFICE.

JOSEPH W. ROUNTREE, OF WASHINGTON, DISTRICT OF COLUMBIA, ASSIGNOR
TO M. J. WINE, OF SAME PLACE.

FILE-CASE.

SPECIFICATION forming part of Letters Patent No. 339,325, dated April 6, 1886.

Application filed June 27, 1885. Serial No. 170,047. (No model.)

To all whom it may concern:

Be it known that I, JOSEPH W. ROUNTREE, a citizen of the United States of America, residing at the city of Washington, in the District of Columbia, have invented a new and useful File-Case, of which the following is a specification.

My invention has relation to improvements in file-cases, the objects being, first, to provide improved means for fastening the side pieces and suspension-lugs in position to the end of the file-box; second, to provide means for regulating and fixing the position of the file-box in its receptacle in the case; and, third, to provide an improved cross-bar for the follower of the file-box.

Heretofore it has been the custom to secure the side pieces and the suspension-lugs to the end board of the file-box independent of each other. This arrangement requires the use of a fastening to each element or part, and the fastening means to be projected into the end board at a point where the greatest strain comes upon the parts; hence they are liable to become loose and the box made shaky.

As heretofore stated, it is one of the objects of my invention to provide means to unite the side pieces and the suspension-lugs to the end board by a single bolt or screw, and thus to hold them firmly in combination.

Also, heretofore no means were provided whereby the position of the file-box in its receptacle in the case could be determined or fixed, the distance to which the box could be set in the case being determined by the depth of the case or the length of the end board; hence in instances where the papers in the box were longer than the end board they were likely to be crumpled and broken by pressure against the back of the case; again, the boards of the back of the file-case being of light stuff, secured to the case by small fastenings, in time become warped, thus making an uneven surface, and causing a series of boxes to set in the receptacles at different distances, and making an irregular front arrangement.

It is the purpose of my improvements to overcome these objectionable features.

My invention therefore consists in an improved side piece for a file-box, formed with an upwardly-extended bracket-arm having a

perforated side ear, as will be hereinafter more fully described.

My invention further consists in a novel combination of means for securing the side pieces and suspension-lugs to the board of the file-box.

My invention further consists in adjustable means, as hereinafter described, for limiting and fixing the position of file-boxes within their receptacles.

My invention also consists in an improved cross-bar for a file-box.

My invention also consists in the novel arrangement and combination of parts, as will be hereinafter more fully described, and specifically pointed out in the claims.

I attain these objects and purposes of my invention by the means illustrated in the accompanying drawings, forming a part of this specification, and wherein—

Figure 1 is a transverse vertical sectional view of a portion of a file-case showing my improvements, and as having one file-box inserted and one withdrawn and suspended.

Fig. 2 is a sectional view taken on the line xx of Fig. 1. Fig. 3 is a detail view in cross-section of the forward connection of the suspension-bar. Fig. 4 is a view of the suspension-bar. Fig. 5 is a view of a portion of the suspension-bar, showing the supporting-lugs at its forward inner end. Fig. 6 is a view of the sliding stop-plate. Fig. 7 is a view of one of the suspension-lugs. Fig. 8 is a perspective view of the completed box. Fig. 9 is a view of the improved cross-bar for the follower, and Fig. 10 is a detail view of the side bars and lugs secured to the end board.

In the drawings similar letters of reference identify like parts.

The letter A designates a portion of a file-box of any of the usual or well-known constructions provided with vertical walls or side pieces, a.

The letters B designate the suspension-bars, of a well-known construction in the general conformation, being formed of metal and having a vertical flange, b, and horizontal flange, b' , said flanges being arranged at right angles to each other. The horizontal flange b' is broken away for a distance, as seen at b'' , for the purpose of permitting the ends of the suspension-lugs attached to the end board of the

file-box to drop through and pass below the line of the flange. The horizontal flange at the forward end of the suspension-bars is turned downward and carried rearward, as at 5 b^4 , which conformation makes a closed end to serve as a bearing or stop for the ends of the suspension-lugs on the bottom of the end board, and thus hold the file-box in suspension. The vertical flange of the suspension-bars is provided with perforations at the forward and rear parts, substantially as shown, and to save material in the main flange, and for convenience of attachment to the case the flange at that portion about the rear perforation, b^5 , is widened. 10

15 My improvements consist in forming on the inner or wall face of the suspension-bars about the forward perforations, b^6 , a lug, b^7 , the perforation of the bar at this point being extended through the lugs, the entrance to one of perforations at this end of the bar being countersunk to receive the head of a screw, and the perforation in the opposite lug and suspension-bar being screw-threaded to receive 20 the threaded end of the fastening-screw. These lugs or projections b^7 are arranged in a hole bored or cut in the vertical partitions of the case and the screw projected through the one into the threaded lug of the other, and thus 25 both suspension-bars are held at that point to the partition by a single fastening, additional security being given by means of the lugs having their seat in the hole in the partition.

30 The letter C designates a sliding stop-plate formed, preferably, with a projecting piece, c , at the front to give broader abutting surface for the end of the suspension-lugs, and provided with a slot, c' , arranged in the direction of the length of the plate. These stop-35 plates are set against the outer faces of the suspension-bars with the slot registering with the rear perforation thereof, and are brought with their forward end faces to about flush 40 with the rear edge of the cut-away part in the flange, and are secured by a clamping-screw, c^2 , passed through the slots in the plates, the suspension-bars, and the partitions. Thus it 45 will be seen that adjacent suspension-bars are held to opposite sides of the same partition-piece by single bolts or screws at each end of the bars. 50

55 The letter D designates a file-box having slotted side pieces, d . These, so far as the general construction of the side pieces and vertical portions secured to the front board of the box are concerned, are of a well-known construction.

60 My improvements, as stated hereinbefore, consist in the novel construction of that part where the side pieces are secured to the end board of the box. At this part the metal of the side piece is extended upward, as at d' , forming a vertical bracket-arm or projection, and on the upper inner side of this vertical bracket-arm is formed a side ear, d^2 , arranged 65 at right angles to the side piece, and having a

perforation, d^3 . To give a neat attachment, and to add security to the connection with the end board, this side ear, d^2 , is preferably formed on the bracket-arm with a shoulder, d^4 , seats 70 d^5 being cut in the end board, to which the ears are fitted. To the outer face of the end board are arranged and secured the suspension-lugs d^6 , having perforations and inwardly-projecting lugs d^7 . The side pieces of the box 75 and these suspension-lugs are secured in relative position to the end board by means of a threaded bolt and nut, d^8 , passed through the ears of the side pieces, the end board, and the suspension-lugs, the several parts at this 80 connection being held secure and firm by this single fastening means.

85 The letter E designates my improved cross-bar. This consists of a metal cross-bar, e , of the usual construction, provided with disks e' at the ends, and cams e^2 to engage in the serrations of the slots in the side pieces.

90 My improvements have special reference to the finger-piece e^3 , which, being designed to carry the cams into engagement, sometimes, when of the usual construction, drops against the face of the follower-board of the box, and in this position it is inconvenient to grasp or manipulate. To avoid this objection I form the finger-piece with a projecting lug, e^4 , 95 directed toward the follower-box, which, when the piece drops down, sets against the follower-board and leaves space for the finger to pass between the finger-piece and the follower-board. 100

Having thus described my improvements, what I claim as my invention, and desire to secure by Letters Patent, is—

1. The combination, with the vertical walls of a file-case having seats formed therein, of the 105 suspension-bars, as B, having side lugs formed thereon to set in the seats in the said walls, and perforations extended through the side lugs, one of said perforations being provided with interior screw-threads, and a fastening-screw projected through both of said side lugs, whereby both suspension-bars are held to the case by a single screw at that point, substantially as described. 110

2. In combination with the front and end 115 boards of a file-box, the side pieces, d , formed with vertical bracket-arms d' , projected above the upper edge of the side piece, and having an inwardly-turned perforated side ear, d^2 , at their upper ends, the suspension-lugs d^6 , and 120 fastening-bolts d^8 , projected through the ears of the bracket, the end boards, and the suspension-lugs, substantially as described. 125

3. In combination with the front and end boards of a file-box, said end boards having 130 seats formed therein to receive the ears of the side pieces, the side pieces formed with vertical bracket-arms projected above the upper edge of the side piece, and having perforated side ears projected from the upper ends of the 130 bracket-arms and set at right angles to the side pieces, with their inner face extended be-

- yond the end face of the side piece, and fastening-bolts projected through the side ears of the bracket, the end board, and the suspension-lugs, substantially as described.
- 5 4. In combination with the suspension-bar of a file-case, the adjustable stop-plate, substantially as described, and for the purpose stated.
5. In combination with a file-case, the suspension-bar B, formed with the perforated lug b', and cut-away portion b'', and an adjustable stop-plate, C, having horizontal slot c', all arranged and combined substantially as described, and for the purpose stated.
6. In combination with the vertical walls of a file-case, the suspension-bars arranged on opposite faces of said wall, and formed with perforated lugs at their forward ends and perforations at their rear ends, and cut-away parts in the horizontal flange thereof, the adjustable 15 sliding plates C, having central slots, and clamping-screws projected through both suspension-bars and the partition of the file-case, substantially as described.
7. In combination with a file-box provided with suspension-lugs on the end boards thereof, and a file-case provided with suspension-bars having horizontal flanges with a portion cut away, a stopping plate or stud adjustably secured to the suspension-bars of the case, whereby the position of the file-boxes in the case is arranged and determined, substantially as described.
8. The improved cross-bar E, formed with a projection, e', extended from the inner face of the finger-piece e'', substantially as described, and for the purpose stated.
- In witness whereof I have hereunto set my hand in the presence of two attesting witnesses.

JOSEPH W. ROUNTREE.
